UNITED STATES PATENT OFFICE.

PATRICK F. DUNDON, OF SAN FRANCISCO, CALIFORNIA.

FURNACE FOR STEAM-BOILERS.

SPECIFICATION forming part of Letters Patent No. 247,546, dated September 27, 1881.

Application filed February 1, 1881. (No model.)

To all whom it may concern:

Be it known that I, PATRICK F. DUNDON, of the city and county of San Francisco, State of California, have invented an Improved Smoke-Consuming Furnace for Steam-Boilers; and I hereby declare the following to be a full, clear, and exact description thereof.

My invention relates to an improvement in that class of furnaces or apparatus which is intended to produce a more perfect and complete combustion of the fuel, and which are known as "smoke-burners."

It consists in the construction of a furnace having a bridge-wall at its rear end, with the top so curved toward the furnace, in combination with a blast of air or steam directed upon the surface of the fuel at an angle, so as to strike it near the bridge-wall, whereby a counter-current will be induced, which will return the smoke, soot, and unburned particles or gases toward the front of the furnace to be projected downward upon the incandescent fuel, where it is ignited and consumed before escaping over the bridge-wall.

Referring to the accompanying drawings for a more complete explanation of my invention, Figure 1 is a longitudinal section of the furnace of a steam-boiler. Fig. 2 is a transverse section. Fig. 3 is a view of another form of boiler, in which the bridge-wall is straight on top. Figs. 4 and 5 are sectional views.

A is a boiler of any suitable construction to which it is desired to apply my invention. B is the furnace-front. C is the furnace having the grate-bars D, upon which the fuel is received.

Behind the grate-bars is the bridge-wall E, which is built up to follow the outline of the bottom of the boiler or the crown of the furnace, and at only a short distance from it. The face of this wall is curved toward the furnace at the top, so as to form a projection or overhang, F, which may preferably be in the form of a curve or partial arch, and it tends to throw the flame and products of combustion toward the front of the furnace before they are allowed to escape over the bridge-wall.

At the front upper portion of the furnace is a pipe, G, which extends across, as shown, and has small perforations made in its lower rear portion, so that steam introduced into the pipe

under pressure will be directed upon the incandescent fuel and strike it obliquely and near the bridge-wall. From this point it glances against the bridge-wall and follows the curve F, thus creating a current over the top of the fuel and toward the front of the furnace. This current catches the smoke, soot, and unconsumed gases which arise from the partially-ignited fuel and prevent them from escaping at once over the bridge-wall, but return them toward the front of the furnace, where they are caught by the steam-jets and thrown down upon the incandescent fuel, so that the combustion is rendered more complete.

I form holes H through the bridge-wall in a line corresponding with the upper surface of the wall. These holes are at such a point above the surface of the fuel as to allow the flame from it to pass through, and this produces a heat which will ignite the smoke and unconsumed gas which may have passed over the wall, so that they will be consumed before they enter the flues or tubes of the boiler. These holes may be horizontal or inclined, and are either formed in the wall, or of sections of pipe which may be built in, with suitable intervals between them.

Steam is furnished to the pipe G from the steam drum or dome or from any desired point, and the steam may be superheated or not, as is found most desirable.

It generally appears, and especially where coal is used as a fuel, that there will be a bed of incandescent fuel at the extreme rear of the furnace, and next to the bridge-wall, and any additions of fuel made by firing are usually near the front, so that the smoke and unconsumed gases produced by the imperfect combustion of this freshly-supplied fuel will arise near the front, and the action of the air or steam blast, as before described, serves to retain them within the furnace, and to bring them into intimate contact with the hottest part of the fuel by the action of the blast. It also causes a flame from the fire to pass through the holes in the wall, and in a slightly-upward direction, on account of the position of the openings, so that it will meet and consume any smoke, soot, or inflammable gases which may have escaped over the bridge-wall.

It will be seen that to produce the best re-

sults the bridge-wall should be carried up near to the bottom of the boiler or to the crown sheet, according to the form of boiler used, so as to equalize the draft at all parts of it. The form of the holes through it is not material; but I have found that when in an inclined position they will be the most effective.

I am aware that the bridge-walls of furnaces have heretofore been made with their upper edges pitched forward; and I am also aware that the upper edges of the bridge-walls have been perforated to allow flame to pass through and meet the escaping unconsumed gases; and hence I do not broadly claim either of these ideas; but I am not aware that a bridge-wall has heretofore been made where the upper edge conformed to the formation of the boiler-shell and also pitched forward; nor am I aware that such a formation of bridge-wall has been combined with a jet of steam or air escaping at a high velocity. Consequently,

Having thus described my invention, what I claim as new, and desire to secure by Letters Patent, is—

1. The bridge-wall of a boiler-furnace having its upper surface approximating in form and approaching to the bottom of the boiler, and with the curved projecting flange or overhang, as shown, in combination with the steam or air blast jet-tube, which directs a blast so as to strike the fuel upon the grate at an angle near the wall, whereby a return-current is induced, substantially as herein described.

2. A boiler-furnace having the air or steam blast jet-tube extending across its front upper portion, so as to deliver a blast obliquely downward upon the fuel, in combination with the inwardly curving or projecting bridge-wall, having its upper edge approaching and conforming to the lower part of the boiler, and provided with the oblique holes or perforations, substantially as herein described.

In witness whereof I have hereunto set my hand.

PATRICK F. DUNDON.
